GARAGE CONSTRUCTION

Application filed May 1, 1929. Serial No. 359,495.

This invention relates to building construction particularly for use in parking or storing motor vehicles wherein ramps are employed.

5 It is an object of this invention to provide a series of ramps within a multi-story building in such a manner that the space is most efficiently utilized for the parking of motor vehicles.

10 Another object of my invention is to devise a multi-story building for the parking of motor vehicles having a novel relationship between the positioning of upgoing and downgoing ramps and the parking areas provided on the several floors.

15 It is a further object of this invention to devise a building construction wherein the ramps are utilized as means of support for the building.

20 Further objects of the invention will appear from the following description, in which I have set forth the preferred embodiments of my invention. It is to be understood that the invention, as defined by the claims, is to be accorded a range of equivalents consistent 25 with the state of the prior art.

Referring to the drawings, Figure 1 is a plan view of a floor of a building employing my novel form of construction.

30 Figure 2 is a cross-sectional elevation on line 2—2 of Figure 1.

Figure 3 is a cross-sectional elevation on line 3—3 of Figure 1.

The numerous building constructions heretofore proposed for the parking of motor vehicles have, because of the layout and car handling facilities employed, been of an unusual or freakish construction. Thus it has been proposed to provide buildings in which 35 the floors are staggered and also to provide ramps extending along the outside of the building. These features render the building unsuitable for other uses, if it subsequently proves desirable to change its type of occupancy, and do not utilize the floor space to best advantage.

I preferably utilize a building having the ordinary "flat slab" construction of reinforced concrete. Thus, as I have shown in 50 the drawings, the building is preferably rec-

tangular with plain side walls and right angle corners, and has a plurality of superposed floors, indicated at 4 to 9 inclusive. Each floor is expediently laid out in such a manner that the most efficient utilization of space is effected in parking the vehicles. 55 Thus, as is shown in Figure 1, single car areas 11 are provided adjacent to walls 12 while double car areas 13 are spaced from areas 11 by intervening aisles 14. Transverse aisles 16 are provided between the double car areas 13 to expedite the transfer of vehicles on the floor. Preferably each one of the several floors is laid out in a manner identical with that of the other floors. The layout shown in 60 Figure 1 is, therefore, that of any of the several floors in the preferred form of the building which I have disclosed herein.

While it has been proposed in some instances heretofore to transport the vehicles 70 between floors by auxiliary means such as lifts or elevators, I prefer to transfer the vehicles by their own power as a faster and more economical handling of them may be thus effected. Accordingly, I provide two series 75 of ramps which are respectively used in going to and from any one of the several floors. The manner in which I prefer the provision of these ramps to be made is best understood by reference to the path over which a vehicle, 80 after entering the building, progresses to the parking area on one of the superposed floors.

Considering first the series of ramps over which a car passes in ascending to one of the upper floors, the first ramp 16, as is shown in 85 Fig. 3, is preferably adjacent to the side A of the building and runs between the first floor 4 and the second floor 5 of the building. The next ramp, indicated at 17, which is cooperatively disposed with 90 respect to the first ramp 16 for the travel of upgoing vehicles, is preferably located adjacent to the opposite side of the building and extends between floors 5 and 6. A vehicle progresses up ramp 16 to the floor 5 95 and then along an aisle space, which is indicated at 18, to the ramp 17 up which it proceeds to the floor 6. To provide access for vehicles to the upper floors a third upgoing ramp 19 is provided adjacent to the side of 100

the building A and superposed above ramp 16, but not adjacent thereto, as will be hereinafter set forth. It may thus be readily seen that a vehicle upon entering the building proceeds along the ramp 16, to the second floor 5 of the building and then along aisle portion 18 of this floor to the second ramp 17 oppositely disposed and raised with respect to the first ramp 16, up which it advances to the third floor 6 of the building. By a similar progress the vehicle may proceed to any one of the higher floors of the building.

Now considering the down going series of ramps, if a car on the third floor 6 is to be removed from the building, it is moved from the floor into aisle portion 21 of that floor and then onto the down going ramp 22 from which it emerges into the aisle portion 23 upon the second floor 5, opposite to the aisle space 18, which is used by cars in proceeding up to the third floor. The vehicle then progresses in the aisle 23 to the ramp 24, down which it proceeds to emerge upon the lower floor 4.

It is to be noted that the cars proceed into and out of the building by paths superposed one above the other and so arranged that vehicles progressing in one direction do not, at any point along their path, intersect. This is particularly illustrated in Figure 1, where a car 26 travelling upwardly enters into aisle space 27 from an upgoing ramp 28. The car then proceeds along the aisle space 27 to upgoing ramp 29, or into one of the parking areas. In like manner a car 31 proceeding downwardly emerges from ramp 32 into aisle space 33, which is opposite to the aisle 27, along which it progresses to enter downgoing ramp 34, which communicates with the floor below. Furthermore, it is to be noted that the ramps extend from an aisle space on one floor to an oppositely positioned aisle on the floor above, and are usually only wide enough for the passage of one car. This manner of providing the ramps results in a very economical layout, since a minimum of available space is devoted to the handling of the cars and the maximum area is available for their storage.

I preferably use the well known flat slab construction for the floors throughout the building of my invention for I have found that it is the most economical type of construction. It is also desirable to have the floors positioned together as closely as is expedient with the type of vehicle being handled, and with the limitations of available construction materials. I have also found it expedient to employ the head frame and method of reinforcing disclosed in my patents, respectively Numbers 1,086,866 and 1,128,912. The method of reinforcing and construction there disclosed enables me, when I utilize the ramp construction herein disclosed, to position the floors adjacent to each other with a minimum distance of approximately ten feet between each floor, since the

use of beams necessary in other types of floors is obviated. This enables a ramp to be used, in the manner I have disclosed, having a slope of about 20%, which is generally considered to be the steepest slope feasible for use in buildings of this character.

To bound the ramps and to enclose them between the floors, I preferably provide side walls 41 extending transversely of the building and adjacent to the sides of the several ramps. By positioning these side walls upon suitable foundations, I am enabled to utilize them as supporting members for the various floors of the building. This reduces the number of columns required in the building and materially simplifies the problems in connection with the construction of the several floors. The ramps and the side walls are thus employed as elements in the building construction.

The space, indicated particularly at 42, bounded by the side wall and the parking area, which is usually unsuitable for the ready parking of cars, is expediently employed as an area for elevators, checking stations, operators' quarters, or for other purposes.

While the side walls preferably extend the full distance between the floors I have also found it to be convenient, in certain instances, to cut away portions of the side walls. This enables a fuller view of the floor to be obtained from the ramps, thus increasing the safety with which a car is driven between floors.

In some instances the construction employed, has been to provide only one side wall along the ramps extending between the floors. The other wall is restricted in height to provide merely a curb or guard along the ramp.

The ramps are usually constructed and are so banked as to facilitate the travel of cars over them. Thus the ramps are positioned in such relationship to the aisle areas, with which they are in direct communication, that a car may proceed with a minimum amount of turning effort on the part of the driver.

I claim:

1. A garage building comprising a plurality of substantially coextensive superposed floors, each of said floors having identical parking areas and spaced parallel aisles on opposite sides of certain of the parking areas, a plurality of spaced supporting walls extending within the building between the spaced parallel aisles and through the superposed floors, spaced inclined relatively narrow ramps joined to said walls and sloping in opposite directions, each ramp being of sufficient length to extend between the parallel aisles on adjacent floors only, said ramps being superposed within the building and occupying only a portion of the area between the adjacent parallel aisles, whereby all up- 115 120 125 130

going and downgoing traffic moves in the same direction.

2. A garage building comprising a plurality of substantially coextensive superposed floors, each of said floors having identical parking areas and spaced parallel aisles on opposite sides of the parking areas, a plurality of spaced supporting walls extending within the building between the spaced parallel aisles and through the superposed floors, longitudinally curved, relatively short, narrow, inclined ramps joined to said walls and sloping in opposite directions, each ramp being of sufficient length to extend between the parallel aisles on adjacent floors only, said ramps being superposed within the building and occupying only a portion of the area between the adjacent parallel aisles, the aisles and ramps being connected to form two series which are arranged with respect to each other whereby all traffic moves in the same direction.

In testimony whereof, I have hereunto set my hand.

25 CHRISTOPHER H. SNYDER.
